UNITED STATES PATENT OFFICE.

ALEXANDER F. BRUHY, OF PLYMOUTH, WISCONSIN.

AUTOMATIC STOP FOR PHONOGRAHS.

1,360,879.

Specification of Letters Patent. Patented Nov. 30, 1920.

Application filed September 27, 1919. Serial No. 326,810.

To all whom it may concern:

Be it known that I, ALEXANDER F. BRUHY, a citizen of the United States, residing at Plymouth, county of Sheboygan, and State of Wisconsin, have invented new and useful Improvements in Automatic Stops for Phonographs, of which the following is a specification.

My invention relates to improvements in phonographs or talking-machines, and especially, to the means employed for stopping the machine at the end of the record being played, or at any other predetermined point of the record that may be desired.

The objects of my invention are to produce a simple, economical, and easily applied attachment, applicable to the conventional type of phonographs or talking-machines, and which is capable of positively, instantly, and automatically stopping the machine at the end of the record being played, or at any predetermined point thereof desired; and, furthermore, if preferred, to combine with such attachment, a cheap and simple means for regulating the speed of the motor, and, hence, the tempo or time in which the record is played, thus obviating the necessity of employing a separate mechanism for this purpose.

Other objects and advantages of the invention will hereinafter appear, and the novel features thereof will be hereinafter described and more particularly pointed out in the appended claims.

Referring to the drawings:

Figure 1 is a plan view of the motor-board of a phonograph of the conventional type, the tone-arm being shown in dotted lines, the record-supporting table being removed, and my invention applied to said motor-board;

Fig. 2 is a transverse vertical sectional view taken on the line 2—2 certain parts being shown in elevation;

Fig. 3, is an enlarged front elevation in detail of my attachment, parts being shown in section for the purpose of better illustration;

Fig. 4 is a detail in plan of the oscillating plunger-supporting bifurcated friction-shoe and the plunger operating in connection therewith; and

Fig. 5 is a detail in elevation, parts being broken away, illustrating a slightly modified form of plunger.

Similar numerals of reference indicate

similar parts in all the figures of the drawings.

In the illustration employed for the purpose of typifying my invention and showing its application, I designate the motor-board of the well known commercial type of phonographs or talking-machines, to the underside of which is bolted, as is usual, the frame 2, of, in this instance, a spring-motor, but which may support a motor driven by any other power.

The motor, which is of the conventional type, in addition to other mechanism hereinafter mentioned, comprises the usual record-supporting shaft 3, at the upper end of which, reduced as at 4, is supported the table 6. This shaft is vertically disposed and has its upper reduced end projected through and above an opening 5 formed in the motor-board. Near its middle, the shaft carries a worm-gear 6^a, and at its lower end is provided with a small pinion 7, the latter meshing with a larger pinion 8, operated through the spring-actuated drum 9, in the manner usual in this class of motors.

A governor-shaft 10, disposed horizontally, is journaled in the frame perpendicular to the shaft 3, and is provided at its inner end with a worm 11, meshing with and driving the worm-gear of the shaft 3. The governor-shaft is further provided at its opposite end with a fixed collar 12, and between the latter and the worm 11, with a sliding collar 13, the latter being the hub of the brake-disk 14. These two collars are connected by flexible straps 15, and the latter, near the middles, carry weights 16. The governor operates in a manner well known, the speed of the shaft serving to bow the straps and thus draw the sliding collar and its disk toward the fixed collar and against a brake-shoe positioned in the path of said disk, whereby the speed of the motor is reduced. The motor is further provided with the usual winding-shaft 17, which latter carries a gear 18, that meshes with and drives a master-gear 19, of the spring-drum, whereby the spring in the latter is placed under the desired tension for operating the motor.

The tone-arm 20, is mounted to swivel in the usual flanged-ring 21, and has supported upon it, in any convenient manner and at its front, a depending striker-arm 23. In this instance, I employ a split clamping-ring 22 for the purpose of supporting the striker-arm, said ring being rigid upon,

and therefore, adapted to move with the arm in the travels of the latter.

Secured upon the upper side of the motor-board, by means of suitable screws, and diagonally disposed upon said board immediately in front of the opening 5 thereof, is an attaching-plate 24, provided at its inner side with an angularly disposed extension 25, in which is located an adjusting-screw 26, the object of which will hereinafter appear. At its outer end the attaching-plate is upturned to form a flange 27, and the latter is, in this instance, provided with a horizontal slot 28.

In a circular opening 29, formed in the plate 24, adjacent its rear end, and depending through a corresponding opening 32, formed in the motor-board, is a vertically movable plunger 30, at the lower end of which may be secured a somewhat enlarged head 31, preferably formed of rubber or some other frictional material. This plunger is positioned vertically opposite the brake-disk 14 of the governor-shaft of the motor, so that when lowered or dropped by gravity the brake-shoe will contact with the perimeter of the brake-disk 14 and thus arrest further rotations of said disk and, hence, the operation of the motor.

If it be desired to combine with the stop-mechanism now partly described, a means for regulating the speed of the motor, this may be accomplished by securing to the plunger 30 so as to depend therefrom and below the head 31 of the plunger, an arm 33, the lower end of which carries a plug 35, preferably of felt, a socket 34, being secured to the lower end of the arm for the purpose of accommodating the said plug.

Above the plate 24, the plunger 30 is provided with a short vertical slot 36, in which engages loosely the reduced inner end of a lever 37, the outer end of which passes through and beyond the slot 28 formed in the flange 27 of the plate 24 and, in this instance, terminates at its outer extremity in a reduced indicator 38, designed to be conveniently moved laterally over a dial 39, divided into degrees and affixed to the upper side of the motor-board, through a knob 40 located on the upper side of the said lever 37.

At its inner end, beyond the opening 29, is a bifurcated or fork-shaped oscillating friction-plate 48, the opposite bifurcations 49 and 50, of which, lie or are disposed at opposite sides of the plunger 30 and are distanced apart slightly greater than is the diameter of said plunger, so that as will be apparent, when one of said bifurcations is in frictional contact with the side of the plunger the opposite bifurcation will be slightly spaced from said plunger and when said bifurcations are out of contact with the plunger the latter is free to move vertically

in said opening 29 of the attaching-plate, all for a purpose hereinafter described.

For the purpose of supporting the mentioned oscillating bifurcated friction-plate 48, and other parts now to be described, I employ a headed bolt 42, passing the same upwardly through the bolt-hole 41, formed near the rear end of and in the attaching-plate 24. Interposed between the upper surface of the attaching-plate 24, and the under surface of the oscillating plate 48, so as to have frictional contact with the latter, and pivotally mounted upon the bolt 42, is a trip-arm 43, which extends rearwardly and terminates in the circular path of the striker-arm 23 carried by the tone-arm. For the purpose of rendering noiseless the contact between the striker-arm and the trip-arm, I preferably provide the latter, at its rear extremity, with a rubber covering 47. Inasmuch as the distance between the tone-arm and the governor-disk of motors will vary, I prefer to construct the trip-arm in overlapping slidable sections 44 and 45, slotting one as at 45^a, and providing the other section with adjusting-screws 46, so that said trip-arm is thereby made extensible and hence the attachment adapted for any type of phonograph or talking-machine.

The inner or longer of the bifurcations 49 and 50 of the oscillating friction-plate 48, has attached thereto one end of a light coiled-spring 51, the opposite end of which may be attached to the end of a U-shaped adjusting-plate 52, overlying the extension 25 of the attaching-plate 24, and being held in adjusted position by the clamping-screw 26, heretofore mentioned. The tendency of this spring, as will be seen, is to normally maintain that bifurcation of the oscillating friction-plate 48 designated 50, in frictional contact with the side of the plunger 30, so that said plunger is retained in position relative to said friction-plate unless said plate is oscillated, when freed it will drop by gravity, the lower end of the plunger, or rather its friction-head 31, then contacting with and arresting the motion of the governor-disk 14 and hence the motor.

Upon the bolt 42, and surmounting the friction-plate 48, is a clamping-nut 54, a spring-washer 53, preferably being interposed between said nut and said plate 48. The nut is sufficiently tightened upon the bolt to cause the desired friction between the plate 48 and the arm 43; that is to say, so that the arm 43 will retain any position in which it is placed and yet be capable of being moved even by the light contact of the striker-arm 23 carried by the tone-arm. Also, in so far as the plate 48 is concerned, the friction between the parts must be sufficient to overcome the tendency of the spring 51.

This completes the construction of my in- 130

vention, and, assuming the motor to be locked against operating, and therefore, the plunger 30 as being lowered so that its head 31 is in contact with the periphery of the 5 governor-disk 14, the operation of adjusting the parts so as to stop the machine at a predetermined point, as, for instance, the end of the record to be played, and for starting the motor, may be described briefly as follows:

The record to be played being in position upon the table 6, the tone-arm is swung so as to bring the stylus or needle to a point on the record where it is desired the machine 15 should be stopped. The operator then swings the trip-arm to a point where it contacts with the depending striker-arm 23, at which point it will be permitted to remain, and the tone-arm is then reversed in its 20 movement so as to bring the stylus or needle at the point of beginning of the record. The operator having adjusted the lever 37 laterally over the dial to permit the motor to operate at the desired speed, said lever is 25 now depressed at its outer end, and, fulcruming upon the lower edge of the slot 28 of the attaching-plate, at its inner end raises the plunger from its contacting position with the governor-disk 14, thus liberating 30 the latter and consequently the motor and permitting the latter to operate. As will be apparent, the speed of the motor, and, hence the time or tempo in which the piece is played, if it be a musical composition, is 35 regulated by the position of the brake-head 35 with reference to the governor-disk, that is to say, by oscillating the lever 37 and hence partially rotating the plunger 30, the plug 35 will be adjusted with relation to the 40 brake-disk 14, it being understood that the more contiguous the plug is to the face of the disk, the less the speed of the motor. When finally the stylus or needle reaches the point upon the record, usually the end, 45 where the striker-arm 23 contacts with the rear end of the trip-arm 44, the latter will be moved laterally a short distance with the travel of the tone-arm, and the frictional contact between the trip-arm and the friction-plate 48 is sufficient to cause said trip 50 arm, when thus moved, to cause an oscillation of said plate in the opposite direction or so that the inner edge of its bifurcation 55 is withdrawn from contact with the side of the plunger, so that the latter is thus 60 liberated from such frictional engagement and falls by gravity to its position against the periphery of the governor-disk. The rotations of the governor-disk, and, hence, 65 the motor, are instantly arrested and the machine thus stopped at the desired point. The trip-arm once having been set to stop the machine at the end of the record, may be permitted to remain in such position, and therefore need not be readjusted for each

succeeding record played. Regardless of the automatic feature of the invention, it will be seen that the machine may be stopped by hand at any intermediate point of the record simply by depressing the plunger by 70 elevating the outer end of the lever 37.

It will be understood, of course, thus the slot 28 may be simply an opening approximating the shape in cross-section of the lever 75 37, so that said lever will simply raise and lower and have no lateral means of adjustment, in which case the brake-arm 33 and parts carried thereby will be omitted and the usual independent timing-means depended upon for timing the motor.

Or, as I have illustrated in Fig. 5, I may provide the head of the plunger with a beveled lower end 56, formed at the bottom of its head 55. By this arrangement and a means for vertically adjusting the plunger, 85 the beveled lower end of the latter may be brought nearer or farther from the periphery of the governor-disk in the same manner as is the head 35 heretofore described, so that the plunger not only acts to arrest the 90 operation of the motor but also to regulate its speed as well.

The mechanism described will be found to be instantaneous in its action, as well as exceedingly positive and absolutely noiseless, there being no contact of metal against metal, the moving parts quickly coming to a noiseless stop the instant the striker-arm contacts with the trip-arm. It will also be observed that the attachment is of a very 100 simple and economical construction, consisting of few and substantial parts, leaving nothing to require future repair or future adjustment; and finally that it is applicable to any and all of the well known makes of 105 phonographs or talking-machines.

Having described my invention, what I claim is:

1. The combination with a phonograph and its motor, of a vertically reciprocating 110 plunger mounted in an opening in the motor-board at one side of the turn-table support and adapted at its lower end to brake upon a moving part of said motor, means for supporting the plunger in its elevated position and out of the braking engagement with the motor, and means carried by the tone-arm for releasing said plunger.

2. The combination with a phonograph 120 and its motor, of a vertically movable gravity plunger mounted in an opening in the motor-board at one side of the turn-table support and adapted by its own weight to fall and brake upon a moving part of said 125 motor, means for supporting the plunger in its elevated position and out of braking engagement with the motor, and means operable by the tone-arm for releasing said plunger.

3. The combination with a phonograph and its motor, of a vertically movable gravity plunger mounted in an opening in the motor-board at one side of the turn-table support and adapted at its lower end to brake upon a moving part of said motor, means for supporting the plunger in its elevated position and out of braking engagement with the motor, and means carried by the tone-arm for releasing said plunger and permitting it to fall by gravity into braking engagement with a moving part of said motor.

4. The combination with a phonograph, and its motor, of a vertically movable plunger mounted in an opening in the motor-board at one side of the turn-table support and adapted at its lower end to brake upon a moving part of said motor, means carried by the motor-board for supporting the plunger in its elevated position and out of braking engagement with the motor, and means carried by the tone-arm for releasing said plunger.

5. The combination with a phonograph, and its motor, of a vertically movable plunger mounted in an opening in the motor-board at one side of the turn-table support and adapted at its lower end to brake upon a moving part of said motor, an oscillating plate carried by said motor-board and engaging and adapted to support the plunger in its elevated position and out of braking engagement with the motor, and means carried by the tone-arm for oscillating said plate to release the said plunger.

6. The combination with a phonograph, and its motor, of a vertically movable plunger mounted in an opening in the motor-board at one side of the turn-table support and adapted at its lower end to brake upon a moving part of said motor, means carried by the motor-board for supporting the plunger in its elevated position and out of braking engagement with the motor, an arm positioned on the motor-board and adapted to operate said latter means to release the plunger, and means carried by the tone-arm for operating said arm.

7. The combination with a phonograph, and its motor, of a vertically movable plunger mounted in an opening in the motor-board at one side of the turn-table support and adapted at its lower end to brake upon a moving part of said motor, means carried by the motor-board for supporting the plunger in its elevated position and out of braking engagement with the motor, an arm positioned on the motor-board and adapted to operate said latter means to release the plunger, said arm being adjustable lengthwise, and means carried by the tone-arm for operating said arm.

8. The combination with a phonograph, and its motor, of a vertically movable plun-

ger mounted in an opening in the motor-board at one side of the turn-table support and adapted at its lower end to brake upon a moving part of said motor, means carried by the motor-board for supporting the plunger in its elevated position and out of braking engagement with the motor, an arm positioned on the motor-board and adapted to operate said latter means to release the plunger, said arm being adjustable laterally, and means carried by the tone-arm for operating said arm.

9. The combination with a phonograph, and its motor, of a vertically movable plunger adapted at its lower end to brake upon a moving part of said motor, a bifurcated oscillating plate embracing said plunger and having one of its arms normally in engagement therewith whereby to support it in its elevated or inoperative position, means for elevating said plunger, means connected with said bifurcated plate for oscillating the same to release the plunger, and means carried by the tone-arm for operating said latter means when said tone-arm has reached a point in its travel where said two means contact.

10. The combination with a phonograph, and its motor, of a vertically movable plunger adapted at its lower end to brake upon a moving part of said motor, a bifurcated oscillating plate embracing said plunger and having one of its arms normally in engagement therewith, whereby to support it in its elevated or inoperative position, means for elevating said plunger, an arm connected with said bifurcated plate for oscillating the same to release the plunger, and striking-means carried by the tone-arm for operating said arm.

11. The combination with a phonograph, and its motor, of a vertically movable plunger adapted at its lower end to brake upon a moving part of said motor, a pivoted bifurcated oscillating plate embracing said plunger and having one of its arms normally in engagement therewith, whereby to support it in its elevated or inoperative position, means for elevating said plunger, an arm pivotally mounted in frictional engagement with said oscillating plate and extending to a point adjacent the tone-arm, and a striking-means carried by the tone-arm and adapted to operate the arm, whereby to oscillate said plate to release said plunger.

12. The combination with a phonograph, its motor-board having an opening and its motor, the latter comprising a governor-disk, of a plunger adapted to reciprocate in the opening in the motor-board at one side of the turn-table support and at its lower end to brake upon said disk, means for reciprocating the plunger vertically away from said disk, means for supporting the plunger in its raised inoperative position, and means

carried by the tone-arm for operating said latter means to release said plunger and permit it to drop and resume braking-engagement with said disk.

5 13. The combination with a phonograph, and its motor, of a reciprocating rotatable plunger mounted in an opening in the motor-board at one side of the turn-table support and adapted at its lower end to brake upon 10 the governor-disk of said motor, a speed regulating device carried by the lower end of the plunger and regulated as to its position with relation to the face of the disk by means of the rotations of said plunger, 15 means for raising and lowering and rotating said plunger, means for holding said plunger out of contact with the disk, and means carried by the tone-arm for operating said latter means for the purpose of releasing 20 said plunger so as to assume braking engagement with the disk.

14. The combination with a phonograph, and its motor, of a reciprocating rotatable plunger mounted in an opening in the motor-board at one side of the turn-table support and adapted at its inner lower end to brake upon 25 the governor-disk of said motor, an arm carried by the plunger and depending to a point in the path of the face of said disk and having a friction-head, means for elevating and rotating said plunger, means for holding said plunger when positioned, and means operable by the movement of the tone-arm for releasing said holding-means when 30 said tone-arm has reached a predetermined point of its travel.

15. The combination with a phonograph, and its motor, of a reciprocating rotatable plunger mounted in an opening in the motor-board at one side of the turn-table support and adapted at its lower end to brake upon 40 the periphery of the governor-disk of said motor an arm carried by the plunger and depending to a position in the path of the face 45 of said disk and having a friction head, means for elevating and rotating said plunger, means for holding said plunger when positioned, an arm for operating said latter means, and a striker carried by the tone-arm 50 and adapted to move said arm when said tone-arm has reached a predetermined point of its travel.

16. The combination with a phonograph, and its motor, of a reciprocating plunger 55 mounted in an opening in the motor-board at one side of the turn-table support and adapted at its lower end to brake upon a moving part of said motor, an operating lever for said plunger pivotally connected at 60 its inner end thereto, a holding-means adapted to oscillate and normally engaging and supporting said plunger in its elevated inoperative position, an arm adjustably mounted upon said holding-means and adapted

when operated to disengage said means and 65 liberate the plunger, and a striker-means carried by the tone-arm and adapted to operate said arm when said tone-arm reaches a predetermined point in its travel.

17. The combination with a phonograph, 70 and its motor, of a vertically reciprocating oscillating plunger adapted when lowered to make braking contact with the disk of said motor, and arm depending from said plunger and carrying a friction head in the path 75 of the face of said disk, a lever fulcrumed, adapted to laterally vibrate and pivotally connected to said plunger so as to elevate and rotate the same, a dial at the outer end of and over which said lever is adapted to 80 move, means for normally holding said plunger in its elevated position, and means carried by the tone-arm for releasing said holding-means when said tone-arm has reached a predetermined point of its travel. 85

18. The combination with a phonograph, and its motor, of an attaching-plate secured upon the motor-board of the machine, said plate having one end upturned and provided with a slot, a vertically reciprocating 90 plunger mounted to oscillate in an opening in the plate and motor-board above the governor-disk of the motor, whereby its lower end will make braking contact with the periphery of said disk when said plunger is 95 lowered, an arm carried by the plunger and depending therefrom to a point opposite the face of said disk and provided with a friction-head a lever pivotally connected to the plunger at one end, passing through, fulcrumed in and laterally movable in the slot of said attaching-plate, a holding-means for supporting the plunger when operated, and means carried by the tone-arm for operating 100 said holding-means to liberate the plunger 105 when said tone-arm has reached a predetermined point of its travel.

19. The combination with a phonograph, and its motor, of an attaching-plate secured upon the motor-board of the machine, said 110 plate having one end upturned and provided with an opening, a lever fulcrumed in said opening, a reciprocating plunger pivotally connected to the inner end of the lever and adapted to be elevated from contact with 115 the disk of the motor by a depression of the outer end of said lever, a bifurcated oscillating friction-plate pivoted upon the attaching-plate and having its bifurcations embracing said plunger, one of which bifurcations is normally in engagement with the plunger for the purpose of supporting the same, a spring for effecting such engagement, an arm pivoted upon and having frictional contact with said bifurcated plate, 120 whereby it is adjustable with relation to the same, and a striking-means carried by the tone-arm and adapted to strike and operate 125

said arm to oscillate the plate and release the plunger when said tone-arm has reached a predetermined point of its travel.

20. The combination with a phonograph, 5 and its motor, of an attaching-plate secured upon the motor-board of the machine, a reciprocating plunger mounted in an opening in the attaching-plate above the governor-disk of the motor and adapted at its 10 lower end to brake thereupon when lowered, a pivot-bolt extending upwardly through the attaching-plate to the rear of the plunger, a bifurcated friction-plate mounted to oscillate upon said bolt and having its arms disposed at opposite sides of said plunger and exceeding in distance apart the diameter 15 of said plunger, a spring connected to one

of said arms and at its opposite end to the attaching-plate, whereby to oscillate said friction-plate so that the opposite arm will 20 engage the plunger, a lever fulcrumed adjacent the plunger and pivoted at its inner end to said plunger, whereby to elevate the same so that its lower end is out of braking- 25 engagement with the disk, an arm mounted upon said pivot-bolt between the attaching-plate and the oscillating friction-plate and extending to a point adjacent the tone-arm, a striker carried by the tone-arm and adapted to operate the latter arm, a spring-washer 30 mounted on the pivot-bolt, and a nut surrounding the washer upon said bolt.

ALEXANDER F. BRUHY.
